(57) **CLAIM**

The ornamental design for sports ball wheel cover, as shown and described.

DESCRIPTION

FIG. 1 is an isometric view of a football wheel cover in accordance with an embodiment of the present invention; FIG. 2 is a front view thereof;

FIG. 3 is a left-side view thereof;

FIG. 4 is a right-side view thereof;

FIG. 5 is a top view thereof;

FIG. 6 is a bottom view thereof;

FIG. 7 is a back view thereof; and,

FIG. 8 is a side view of the football wheel cover of FIG. 1, illustrating its mounting position on a wheel drawn in phantom.

The pattern of circles on the football-shaped sports ball wheel cover is understood to be repeated uniformly throughout the surface of the wheel cover.

The broken line showing of environment is for illustrative purposes only and forms no part of the claimed design.
